UNITED STATES PATENT OFFICE.

MAGLOIS P. DU PRAY, OF TRENTON, NEW JERSEY.

DRAW-OFF MECHANISM FOR LOOMS.

1,357,968.

Specification of Letters Patent.

Patented Nov. 9, 1920.

Application filed September 14, 1917. Serial No. 191,340.

To all whom it may concern:

Be it known that I, MAGLOIS P. DU PRAY, a citizen of the United States, residing at Trenton, in the county of Mercer and State 5 of New Jersey, have invented certain new and useful Improvements in Draw-Off Mechanism for Looms, of which the following is a specification.

This invention relates to draw-off mechanism for looms; and it comprises rolls journaled in juxtaposition to the weaving surface from which the fabric is to be drawn, one roll being adjustable with respect to the other, and each roll provided with mechanism 10 for penetrating the fabric and with means for withdrawing the penetrating mechanism from the fabric; and it also comprises certain combination of parts and details in draw-off or woven fabric take-up 15 mechanism; all as more fully hereinafter set forth and as claimed.

The draw-off mechanism is particularly useful in combination with circular looms weaving multi-ply circular fabric in accordance 20 with the process and apparatus described and claimed in my copending application Serial Number 72,152, filed January 14, 1916. In the said copending application I have described and claimed a process of weaving multi-ply tubular fabrics which comprises preliminarily weaving one 25 ply around a weaving surface, advancing that ply to another weaving surface and weaving a second ply upon the first ply, and mechanism which comprises two weaving 30 surfaces, means for preliminarily weaving one ply of tubular fabric around one weaving surface, means for advancing that ply to the other weaving surface and means for 35 weaving the first ply upon the second ply at the second weaving surface. Details of the means for advancing one ply from the first weaving surface to the second weaving surface are specifically the subject of 40 45 this application.

While the draw-off mechanism or the woven fabric take-up of this application is useful in connection with circular looms weaving one ply of fabric, it is particularly 50 advantageous in use with the loom described and claimed in my said copending application when used for making multi-ply fabric.

In weaving multi-ply tubular fabric it is necessary to simultaneously advance both 55 plies from the first weaving surface to the second and to accomplish this I provide my

draw-off mechanism or woven fabric take-up with a plurality of pins which are positively and gradually projected from the surfaces of the rolls and which are advantageously of a length sufficient to penetrate the first ply of fabric and to engage the second or inner ply. These pins are normally held in retracted position by means of springs or equivalent devices but may be 60 65 positively withdrawn from the fabric as the rolls revolve.

In the accompanying drawings showing a specific embodiment of the invention,

Figure 1 is a segmental front elevation 70 showing the mechanical and manual means for operating the draw-off mechanism;

Fig. 2 is a top plan view, the outline of the loom being in dotted lines;

Fig. 3 is a transverse section through the 75 rolls on an enlarged scale;

Fig. 4 is a segmental top plan view of the roll partly in section;

Fig. 5 is a detail in perspective of one of the take-up roll grip or pin bars; and 80

Fig. 6 is a sectional detail of the drive and release mechanism.

Referring to the drawings, the main shaft 1 for driving the loom is provided with a friction wheel 2 having a band 3 of leather 85 or similar material. The friction wheel is splined upon the shaft and is provided with a collar 4 having a recessed portion 5 adapted to be engaged by the pin 6 carried by arm 7 in screw-threaded engagement with the screw 8. This arrangement permits adjustment of the wheel 2 upon the shaft and controls the speed of rotation of the take-up rolls as will more fully herein-after appear. The friction wheel 2 is normally in engagement with the driven disk 9 which is carried by the vertical shaft 10 supported by the upright A of the loom. The driven disk 9 is normally spring-pressed against the friction wheel 2 by means 95 of the spring 12, and is keyed to the shaft 10 to rotate therewith by means of a feather 11 permitting vertical movement. The disk is provided with a grooved collar 13 which is embraced by the lever 14 pivoted at 15 100 to the upright A. Rod 16 is in engagement with this lever and is provided at its top with a strap 17 in engagement with the eccentric 18 carried by the hand lever 19 suitably journaled on arm 20 carried by sleeve 21 in engagement with the upright 105 A. The rod 16 may be adjusted by means

of the screw threads 22 and nut 23. Normally the friction wheel 2 drives the driven disk 9 at a rate of speed determined by the position of the driving wheel upon the main shaft. When it is desired to disengage the driving and driven wheels the hand lever 19 is thrown downwardly, thus lifting the rod 16 and the disk 9 away from the driving wheel 2. The shaft 10 is provided at its upper extremity with a beveled pinion 24 engaging the beveled pinion 25 carried by the horizontal draw-off mechanism operating shaft 26.

This shaft in turn is provided with oppositely disposed worms 27 and 28 engaging the gears 29 and 30 respectively, and these gears drive shafts 31 and 32 on which are keyed gears 33 and 34 which mesh with two spurs one of which (36) is shown, Fig. 4. These last mentioned spurs drive the shafts 37 and 38 operating the draw-off rolls. Adjacent the shaft 26 and preferably held at an angle thereto by means of the knuckle joint 39 is a shaft 40 normally in rotation. The shaft 41 may be placed in engagement with shaft 40 through the clutch mechanism 42 operated by the lever 43 and held in position by ratchet 44. Shaft 41 carries manually operated handwheel 45. The shafts 40 and 41 are held at an angle to shaft 26 to permit room for the warp tensioning or evening rolls shown in dotted lines at 46. The handwheel is adapted to be locked to the shaft 40 to initially draw off the woven fabric, or to be released therefrom, when the woven fabric mechanism will be constantly driven from the main shaft.

The take-up for the woven fabric comprises two rolls 50 and 51, the latter being free to revolve in journal boxes 52 while the former is free to revolve in journal boxes 53. The roll 50 is forced toward roll 51 through the pressure of the spring 54 having pressure adjustment at the rear through set screw 55 bearing on the shouldered washer 56. Rolls 50 and 51 are provided on their peripheries with a plurality of longitudinal slots 57 housing gripping pin bars 58. The pins 59 advantageously integral with these bars are of sufficient length to penetrate the outer ply of fabric and to engage the inner ply at least to some extent whereby, as the rolls rotate, these pins pull the fabric from the weaving pin and maintain an even tension on both plies. The pins should be of as small diameter as is consistent with the requisite strength in order that they may not injuriously affect the fabric. Since the pins are operated in a radial direction there might be a tendency to tear the fabric and therefore, in order to overcome this, the bars 58 carrying the pins are normally held below the surface of the rolls by small springs 60 placed between the depressions

or off-set portions 61 in the bars and the bands 62 surrounding the rolls at either end. These off-set portions of the bars formed by the depressions 61 serve as guiding means operating in engagement with shoulders 63 in the roller grooves 64. These bars 58 are advantageously provided on either side with roller bearings 65 which engage cam plates 66 integral with the boxes 52 and 53. The cams 67 on the cam plates 66 serve to force the pin bars outwardly from the rolls and to push the pin into the fabric just at the point of nearest approach of the peripheries of the roller, thus preventing crowding of the fabric between the pins, which would happen if the pins were fixed unyieldingly in the rolls. Ordinarily the springs 60 will serve to withdraw the pins from the fabric, but in order that there may be positive means for accomplishing this I place the guide plates 68 in position to engage the roller bearings 65 and force the bars back into the slots. Set screw 69 serves for adjustment of roll 51 while roll 50 is yieldingly held in position through the screw 55—54, arrangement described.

What I claim is:—

1. The combination with a circular loom having a weaving pin, of a pair of adjacent rolls positioned with their approaching faces in substantial alinement with the weaving pin but spaced sufficiently far apart to permit the fabric from the weaving pin to pass between them, means for rotating the said rolls in a direction away from the weaving pin, bars on the faces of the rolls adapted to be pressed against the fabric, means for resisting outward movement of said bars and means for forcing said bars outwardly from the rolls as opposite pairs of the bars approach each other due to the rotation of the rolls.

2. The combination with a circular loom having a weaving pin, of a pair of adjacent rolls positioned with their approaching faces in substantial alinement with the weaving pin but spaced sufficiently far apart to permit the fabric from the weaving pin to pass between them, means for rotating the said rolls in a direction away from the weaving pin, bars on the faces of the rolls adapted to be pressed against the fabric, means for resisting outward movement of said bars, means for forcing said bars outwardly from the rolls as opposite pairs of said bars approach each other due to the rotation of the rolls, and additional means for positively withdrawing the bars as they recede from each other due to the rotation of the rolls.

3. The combination with a circular loom having a weaving pin, of a pair of adjacent rolls positioned with their approaching faces in substantial alinement with the weaving pin but spaced sufficiently far apart

to permit the fabric from the weaving pin to pass between them, means for rotating the said rolls in a direction away from the weaving pin, bars provided with gripping pins on the faces of the rolls adapted to be pressed against the fabric, means for resisting outward movement of said bars, and means for forcing said bars outwardly from the rolls as opposite pairs of the bars approach each other due to the rotation of the rolls.

4. The combination with a circular loom having a weaving pin, of a pair of adjacent rolls positioned with their approaching faces in substantial alinement with the weaving pin but spaced sufficiently far apart to permit the fabric from the weaving pin to pass between them, means for rotating the said rolls in a direction away from the weaving pin, bars provided with gripping pins on the faces of the rolls adapted to be pressed against the fabric, means for resisting outward movement of said bars, means for forcing said bars outwardly from the rolls as opposite pairs of said bars approach each other due to the rotation of the rolls, and additional means for positively withdrawing the bars as they recede from each other due to the rotation of the rolls.

5. The combination with a circular loom having a weaving pin, of a pair of adjacent rolls positioned with their approaching faces in substantial alinement with the weaving pin but spaced sufficiently far apart to permit the fabric from the weaving pin to pass between them, recesses in said rolls, gripping bars arranged in said recesses and adapted to be pressed against the fabric, means for resisting outward movement of said bars, means for rotating said rolls in a direction away from the weaving pin, and means for forcing said bars outwardly from the rolls as the opposite pairs of the bars approach each other due to the rotation of the rolls.

6. The combination with a circular loom having a weaving pin, of a pair of adjacent rolls positioned with their approaching faces in substantial alinement with the weaving pin but spaced sufficiently far apart to permit the fabric from the weaving pin to pass between them, recesses in said rolls, gripping bars provided with pins and arranged in said recesses and adapted to be pressed against the fabric, means for resisting outward movement of said bars, means for rotating said rolls in a direction away from the weaving pin, and means for forcing said bars outwardly from the rolls as the opposite pairs of the bars approach each other due to the rotation of the rolls.

7. In a take-up device for circular looms, the combination of a pair of rolls each provided with longitudinal slots, springs in said slots, bars in said slots normally retracted

toward the center of the rolls by said springs, means adjacent the rolls for engaging the said extremities of the bars and over which the said extremities ride, projections on said means at the points of nearest approach of the peripheries of the said rolls adapted to force the said bars outwardly whereby they engage the fabric, and means in addition to the said springs to positively retract said bars.

8. In a take-up device for circular looms, the combination of a pair of rolls each provided with longitudinal slots, springs in said slot, bars in said slots normally retracted toward the center of the rolls by said springs, means adjacent the rolls for engaging the extremities of the bars and over which the said extremities ride, projections on said means at the points of nearest approach of the peripheries of the said rolls adapted to force the said bars outwardly whereby they engage the fabric, and means comprising springs located at the extremities of each roll adapted to engage the extremities of the said bars and to positively force the bars back into their recesses.

9. A take-up device for looms, a pair of rolls provided with means on their peripheries for engaging the fabric, means to rotate the rolls, means for changing the speed of rotation of the rolls and means for throwing the speed changing means out of operation.

10. A take-up device for looms comprising a pair of rolls provided with slots on their peripheries, bars located in the slots, depressions at either end of the bars, springs located in said depressions, bands engaging the extremities of the springs whereby they normally tend to depress the bars in said slots, means on the bars for engaging bar operating means, and bar operating means arranged to force the bars outwardly against the tension of said springs when the rolls have revolved to predetermined points.

11. A take-up device for looms comprising a pair of rolls provided with slots on their peripheries, bars located in the slots, depressions at either end of the bars, springs located in said depressions, bands engaging the extremities of the springs whereby they normally tend to depress the bars in said slots, means on the bars for engaging bar operating means, bar operating means arranged to force the bars outwardly against the tension of said springs when the rolls have revolved to predetermined points, and means for engaging the bars to assist the springs in retracting the bars in said slots.

12. A take up device for looms comprising a pair of rolls provided with slots on their peripheries, bars located in said slots and carrying outwardly extending pins, bands surrounding the outer ends of the bars, springs interposed between the bars

and bands and normally forcing the bars inwardly, and means for engaging the outer ends of the bars to force the same outwardly against the tension of the springs.

5 13. A take up device for looms comprising a pair of rolls provided with slots on their periphery, bars located in said slots and carrying outwardly extending pins, bands surrounding the outer ends of the
10 bars, springs interposed between the bars

and bands and normally forcing the bars inwardly, means on the outer ends of the bars for engaging bar operating means, and bar operating means arranged to force the bars outwardly against the tension of the 15 said springs when the rolls have revolved to predetermined points.

In testimony whereof I affix my signature.

MAGLOIS P. DU PRAY.
